UNITED STATES PATENT OFFICE.

ERNEST DVORACEK, OF MAYNARD, OHIO.

RAIL-JOINT.

1,111,887.

Specification of Letters Patent.

Patented Sept. 29, 1914.

Application filed June 27, 1914. Serial No. 847,634.

To all whom it may concern:

Be it known that I, ERNEST DVORACEK, a subject of the Emperor of Germany, residing at Maynard, in the county of Belmont 5 and State of Ohio, have invented certain new and useful Improvements in Rail-Joints; and I do hereby declare the following to be a full, clear, and exact description of the invention, such as will enable others 10 skilled in the art to which it appertains to make and use the same.

My invention relates to improvements in rail joints and resides in the provision of a simple and effective device that is particularly 15 designed to secure the ends of broken rails temporarily in mines and other places where a great deal of traffic is had and breaking of the rails of the track is frequent.

An important object of my invention is 20 to provide a rail joint of the character described that is so constructed as to support the rails without necessitating the placing of a tie thereunder, said device being particularly useful when tracks are to be re- 25 paired and old rails removed and new ones placed in position, especially in mines where great numbers of cars of ore are carried over the tracks and a delay occasioned through breakage or derangement of a rail is dis- 30 astrous to the workings of the mines.

My invention contemplates obviating all objectionable features above described so that rails when broken may be securely and reliably joined and supported without re- 35 quiring much time.

The above and additional objects are accomplished by such means as are illustrated in the accompanying drawings, described in the following specification and then more 40 particularly pointed out as claimed.

With reference to the drawings, wherein I have illustrated the preferred embodiment of my invention as it is reduced to practice, and throughout the several views of which 45 similar reference numerals designate corresponding parts, Figure 1 is a side elevation of a rail showing my improved joint device securing the ends of a broken rail in position, Fig. 2 is a transverse sectional view taken through the rail and showing my improved joint applied thereto, and Fig. 3 is a detail perspective view of one of the supporting and rail clamping members of the joint removed from the rail.

55 Referring to the drawings by characters of reference, the numerals 1 and 2 designate

the end portions of a broken rail and 3 my improved rail joint as an entirety. The rail joint consists of a pair of angular fish plates 4 and 5 so shaped as to conform to the 60 shape of the web and base portions of the rail ends 1 and 2 and of sufficient length to overlap the ends a considerable distance. A plurality, preferably four clamping members 6 designated 6 as an entirety are employed 65 to clamp the fish plates 4 and 5 in position so as to securely hold the rail ends 1 and 2 against derangement. These clamping members 6 are arranged in pairs, a pair being arranged adjacent the end of each 70 rail end as clearly shown in Fig. 1 in the drawings. These members 6 also act to support the rails in such manner that the necessity of employing a tie is eliminated. Each of the clamping members consists of a rec- 75 tangular engaging portion 7 that is designed to engage the under face of the rail bases and is provided at its ends with depending flanges 8, to engage the ground or road bed so that the portion 7 is spaced from the 80 ground or road bed. Laterally extending flanges 9 and 10 are formed on the free or lower edges of the flanges 8 and act as seats to engage the road bed or ground to provide a bearing surface for the clamping members. 85 The flange 9 is bent back upon itself to provide an overlying portion 11 slightly engaging the upper face of the flange 9 and an upstanding or vertical portion 12 engaging the outer face of the flange adjacent 90 thereto. The upstanding portion 12 is extended upwardly and inwardly and bent from its longitudinal center to provide an approximately V-shaped rail clamping jaw 13 that is designed to engage the inner half 95 of the rail bases. The portions 13 are disposed upwardly and inwardly from the inner ends of the portions 7. A removable clamping jaw 14 similar to the one 13 and provided with an L-shaped body 15 is 100 mounted upon the flanges 8 and 10 at the outer faces thereof and arranged to coöperate with the one 13. The flange 10 is provided with upwardly offset and spaced arms 16 at its outer end and designed to coöperate 105 with a locking tongue 17 formed integral on the outer end of the L-shaped body portion 15. This tongue 17 is reduced with relation to the body 15 and provided with an enlarged outer end 18 which is offset with 110 relation to said portion of the tongue so that it may be disposed beneath the arms

16 and the body portion 15 on top of the flange 10. A bolt 19 is inserted through the flange 8 and upstanding portion 12 with its head engaging the outer face of the upstanding portion 12 and extended through the other flange 8 and upstanding portion of the L-shaped body portion 15. A nut 20 is turned on the screw threaded terminal of the bolt 19 and serves to hold the clamping member 14 in position. The bolts 19 increase the rigidity and strength of the clamping members 6 thus insuring a reliable supporting of the rail ends.

To remove the clamping members 14 it is only necessary to draw the bolt 19 after taking the nut 20 therefrom and move the jaw 14 outwardly from the portion 7 so that the locking tongue 17 is moved out of locking coöperation with the arms 16. The arms 16 in being offset upwardly and the tongue 17 in being provided with a downwardly offset portion 18 insures the ready locking and unlocking action.

In operation when it is desired to secure the broken ends of a rail, and temporarily secure the proper rail end while a new track is being laid, it is simply necessary to apply the fish plates 4 and 5 as described and secure them by means of the clamping members 6 which also act as supports for the rails as well as to clamp them to one another.

In practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as set forth.

What is claimed is:—

1. A rail joint consisting of angular fish plates, clamping means to clamp the fish plates to the rails consisting of a rectangular rail base supporting and engaging portion, depending flanges formed on the ends 50 of said portion, laterally extending flanges formed on the ends of said depending flanges to rest flat upon the road bed or ground, a fixed rail clamping jaw carried adjacent one end of said rail base engaging and supporting portion, a removable jaw carried at the other end of said rail base supporting and engaging portion, a locking tongue carried by said removable jaw, arms carried by the laterally extending flanges, one of the laterally extending flanges to coöperate with the

locking tongue to hold the removable jaws against upward movement, and a bolt inserted through the depending flanges and fixed and removable jaws.

2. A rail joint consisting of fish plates to 65 overlie the ends of rails and sides thereof and means to clamp the fish plates to the rails and supports for the rails consisting of a rail base engaging and supporting portion approximately the same width as the base of the rails, depending flanges on the ends of said rail base engaging and supporting portion to support the rail in special relation to the ground or road bed, laterally extending flanges acting as feet formed on the free 75 ends of said depending flanges and to rest flat upon the road bed or ground, and means to clamp the fish plates to the rails carried adjacent to the ends of said rail base engaging and supporting portion.

3. A rail joint consisting of fish plates to overlie the ends of rails and sides thereof and means to clamp the fish plates to the rails and supports for the rails consisting of a rail base engaging and supporting portion approximately the same width as the base of the rails, depending flanges on the ends of said rail base engaging and supporting portion to support the rail in spaced relation to the ground or road bed, laterally 85 extending flanges acting as feet formed on the free ends of said depending flanges and to rest flat upon the road bed or ground, and means to clamp the fish plates to the rails carried adjacent to the ends of said rail base 90 engaging and supporting portion, consisting of a movable clamping jaw, a stationary clamping jaw, a bolt inserted through the depending flanges and jaws, and a nut turned on one end of said bolt.

4. A rail joint consisting of angular fish plates, clamping means to clamp the fish plates to the rails consisting of a rail base supporting and engaging portion, depending flanges formed on the ends of said portions, laterally extending flanges formed on the ends of said depending flanges, a rail clamping jaw carried adjacent to one end of said rail base engaging and supporting portion, an adjustable jaw carried at the other end 105 of said rail base supporting portion, and a locking tongue carried by said removable jaw and arranged to interlock with the adjacent lateral flange.

In testimony whereof I affix my signature 115 in presence of two witnesses.

ERNEST DVORACEK.
